REED M. LEWIS, OF ALIQUIPPA, PENNSYLVANIA.

RAILWAY SIGNALING SYSTEM.

1,210,816.

Specification of Letters Patent.

Patented Jan. 2, 1917.

Application filed November 4, 1913. Serial No. 799,143.

To all whom it may concern:

Be it known that I, REED M. LEWIS, a citizen of the United States, residing at Aliquippa, in the county of Beaver and State of Pennsylvania, have discovered or invented a new and useful Improvement in Railway Signaling Systems, of which improvement the following is a specification.

My invention relates to a system for operating signals disposed at predetermined intervals along a railway, forming blocks or sections, to indicate the presence, or not, as the case may be, to those in charge of a car or train of cars following the same, whether or not a car or train of cars occupies the preceding block.

The invention has for its object to provide a signal system wherein each block or section involves the Wheatstone bridge principle, the car or cars entering and passing through a block serving to disturb the balance and cause a signal to be displayed indicating occupancy of that particular block and immediately after passing out of said block cause the balance to be restored and the signal to indicate that said block is clear or unoccupied.

In the accompanying drawings, forming a part of this specification, I have illustrated an application of my invention to a railway system, in which drawings—

Figure 1 is a diagrammatic view of said system and railway to which it is applied. Fig. 2 is a diagrammatic view of the electric equipment of the car. Fig. 3 is a modification of the block terminal connections.

As shown in Fig. 1, a simplified system of railway is employed for the purpose of more clearly illustrating the application of my improved signal system thereto, in which railway system the numeral 1 indicates the generator, the overhead trolley-wire 2 serving as the outgoing current conductor and the track rails 3 as the return current conductor of the circuit, a car 4, provided with a trolley pole 4; being also shown in connection with said system.

In applying my improvement to the above described railway system, I space off the trolley wire 2 thereof into the desired number and lengths of blocks, of which but two complete blocks are here illustrated as ex-

tending from the terminals A and B and from terminals B to C. From the terminals A to B of the one block, I arrange a paralleling conductor 5, connecting one end thereof to the terminal A and the other end thereof to the terminal B, the next succeeding block having a similar conductor 5 having one of its ends connecting the trolley wire 60 at the terminal B and the other end thereof to the terminal C, the remaining blocks (not shown) throughout the system being each provided with a similar wire 5 connecting at its terminals to the trolley-wire, constituting, practically, a paralleling secondary to the trolley-wire and connects thereto at its ends and at spaced intervals.

In each block is arranged a relay magnet 6, which is connected across the block to 70 the trolley conductor 2 and conductor 5 by a wire 7, said trolley conductor, the conductor 5 and wire 7 having the relay connected thereto, corresponding in principle to the well known Wheatstone bridge instrument. 75

In connecting the conducting wire 7 with the conductor 5, I prefer that there be included in the circuit of said conductor 5, of each block, a resistance 8 and that the terminal of the said wire 7 thereat be provided 80 with a suitable movable contact 9 therefor capable of adjustment, then by means of varying the point of which the said contact 9 engages with the resistance 8 the block may be so balanced that no matter how 85 much current may be flowing along the trolley conductor the relay 6 will not be energized.

The relay of each block is employed to control a suitable independent signal by the 90 opening and closing of signal operating circuit, the simple form for each block here shown as an illustration, comprising a circuit 10 having a lamp 11 therein, one end of which circuit is connected to the armature 95 12 of the relay and the other to a fixed contact B in the path of said armature.

In practice, if it be assumed that the car 4 has just entered the block (as shown), then the drawing of the current in the ordinary 100 course down the trolley pole to and through the car to the track 3, from the trolley conductor unbalances the system in that block, causing the relay therein to be energized

and attract its armature 12, which armature is then brought into engagement with the contact 13, closing the circuit 10 and causing the lamp 11 to be lighted and thereby indicate the presence of a car in that block. The signal circuit 10 remains closed and the signal lamp lighted in this block (as shown) until the car has passed into the next succeeding block, the passing of the car out of said block permitting reestablishing of the balance therein and causing the relay magnet to become deenergized, thus releasing its armature and opening the signal circuit said signal lamp then being extinguished and indicating that said block is clear.

As the car passes into and from each succeeding block the above described operation is repeated.

In Fig. 2, of the car equipment, I have shown a relay the magnet 14 thereof being connected in series with the wire 15 from the trolley pole 4 to the controller 16 and the armature 17 thereof connected by a branch arm 18 to said wire 15. A further branch connection 19 is taken from the circuit wire 20, of the usual connection to the wheel axle or other parts of the car, and terminates in the fixed contact 21, said branch 19 having a suitable resistance 22 connected therein. From this circuit wire 20 is shown the usual branch connections 23 and 24 for the lamps 25 and air brake device 26, the latter branch being connected to the wire 15, and the branch 26 leading to the motor 27 and the controller 16.

Ordinarily the magnet 14 of the relay is energized and the armature 17 thereof attracted thereby, as shown, but should there at any time not be sufficient current drawn from the trolley conductor to cause the system of any block through which a car may be passing to become unbalanced, and thereby prevent the block relay 6 to be energized, then the relay 14 will be deenergized to such extent as to release its armature 17 and cause it to engage the contact 21, thus completing a circuit through the branch 19 and permitting sufficient current to pass through the block relay 6 as will energize the same and insure operating the signal.

In Fig. 3, I have shown a modified form of connecting the ends of the paralleling conductors 5 with the trolley conductor 2, by overlapping the connections, as shown, said overlapping of the system of each block causes the relay 6 in the next succeeding block to respond just before the trolley passes out of the preceding block.

I claim as my invention and desire to secure by Letters Patent:

1. In a railway signal system, a continuous trolley conductor connected with a source of electrical energy, a plurality of paralleling branch conductors each connected at both ends to said trolley conductor

at spaced intervals forming blocks, a signal device for each block and a signal controlling circuit connected with the trolley conductor and with the branch conductor of each block.

2. In a railway signal system, a continuous trolley conductor connected with a source of electrical energy, a plurality of paralleling branch conductors connected at both ends to said trolley conductor at spaced intervals forming blocks, a signal device for each block, and a signal controlling device positively connected with the trolley conductor and branch conductor of each block.

3. In a railway signal system, a continuous trolley conductor connected with a source of electrical energy, a plurality of paralleling branch conductors each connected at both ends to said trolley conductor at spaced intervals forming blocks, each of said branch conductors having a resistance therein, a signal device for each block, and a signal controlling device connected at one end to the trolley conductor and at the other end to the branch conductor of each block.

4. In a railway signal system, a continuous trolley conductor connected with a source of electrical energy, a plurality of paralleling branch conductors each connected at both ends to said trolley conductor at spaced intervals forming blocks, a signal device for each block, a signal controlling device connected with the trolley conductor and the branch conductor of each block, and means carried by the car to automatically increase the current to and insure operating of the signal controlling device when the current otherwise is not sufficient.

5. In a railway signal system, a continuous trolley conductor connected with a source of electrical energy, a plurality of paralleling branch conductors each connected at both ends to said trolley conductor at spaced intervals forming blocks, a signal device for each block, a signal controlling device connected with the trolley conductor and branch conductor of each block, and means to vary the resistance of the circuit in the branch conductor of each block.

6. In a railway signal system, a continuous trolley conductor connected with a source of electrical energy, a plurality of paralleling branch conductors each connected at both ends to said trolley conductor at spaced intervals forming blocks, a signal device for each block, a signal controlling device connected with the trolley conductor and branch conductor of each block, the branch conductor of each block where the controlling device connects therewith having means to vary the resistance therein, and means carried by the car to automatically increase the current to and insure operating of the signal controlling device when the current otherwise is not sufficient.

7. In a railway signal system, the combination with a continuous trolley conductor, a branch conductor connected thereto at both of its ends, and a signal operating circuit connected across and to said trolley conductor and branch conductor.

In testimony whereof, I have hereunto

signed my name in the presence of two subscribing witnesses.

REED M. LEWIS.
